UNITED STATES PATENT OFFICE.

PHILO S. EWINS, OF WEST BERKSHIRE, VERMONT.

SORGHUM-EVAPORATOR.

SPECIFICATION forming part of Letters Patent No. 284,123, dated August 28, 1883.

Application filed May 18, 1883. (No model.)

To all whom it may concern:

Be it known that I, PHILO S. EWINS, a citizen of the United States, residing at West Berkshire, in the county of Franklin and State of Vermont, have invented certain new and useful Improvements in Sorghum-Evaporators; and I do hereby declare the following to be a full, clear, and exact description of the invention, such as will enable others skilled in the art to which it appertains to make and use the same.

My invention relates to sorghum-evaporators, the purpose of which is to thoroughly utilize the heat while at its greatest intensity at the point where most desired—namely, at the boiler—to permit the products of combustion to pass, under proper regulation, through the return-flues of said evaporating pan; to increase the heating-surface of the evaporating-pan; to permit the removal of the boiler from the arch and the direction of the heat and flame immediately into the return-flues; to enable the products of combustion to be directed into one or more groups of return-flues, as desired, and to protect the sirup-compartments from too intense heat, thereby preventing the scorching or discoloration of the sirup.

To these ends my invention consists of the parts and combination of devices substantially as hereinafter described, and particularly pointed out in the claims.

Referring to the annexed drawings, Figure 1 is a plan view of my improved sorghum-evaporator. Fig. 2 is a longitudinal vertical section on line $x-x$, Fig. 1. Fig. 3 is a transverse section on line $y-y$ of Fig. 2. Fig. 4 is a similar section on line $Z-Z$ of Fig. 2, and Fig. 5 is a cross-section on line $z-z$ of Fig. 2.

Corresponding parts in the several figures are indicated by similar letters of reference.

In the accompanying drawings, A marks the furnace, having grates a , door a' , and adapted to permit my improved sorghum-evaporator, with its accompanying mechanism, to rest upon its walls and form the top thereof.

B represents the boiler, placed upon a cast-metal frame, C, which latter in turn rests on the walls of the furnace at its rear end. The boiler is provided with a number of pipes, b , depending from its bottom into the space in

the frame C, said pipes having their lower ends closed and arranged alternately in parallel lines, as clearly shown, so as to interfere with and arrest the currents of heat and cause them to act upon the saccharine liquid in the pipes and boiler. The boiler has a spout, b' , to allow the liquid to pass therefrom into the first of a number of sections into which the evaporating-pan D is, by partitions d , longitudinally divided. With the exception of the last section, which is subdivided by the partition e into two parts, termed the "sirup-compartments," each section is provided with a group or set of flues, E, passing through the pan and extending forward into the smoke-box F, to which they are connected by an ordinary expansion-joint to allow for the expansion and contraction of said pipes. The rear end of the pan D rests on the bottom of the frame C, while its forward end rests on the plate G, arranged on the walls of the furnace. The smoke-box is provided with the ordinary smoke-exit, f ; a pair of doors, f' , at its front to permit the flues to be cleaned, a sliding damper, f'' , in its bottom to allow the smoke, &c., to pass from the fire-box directly into the smoke-box, and a sliding register-damper, f''' , arranged out of contact with the flues E, so as to imperfectly arrest the draft when said damper is drawn out. With the exception of the doors f' , the foregoing parts are particularly set forth in the patent granted to me July 18, 1882, and numbered 261,325.

Between the flues in the sections of the evaporating-pan D, and at the partitions d , the bottom of said evaporating-pan is crimped, as clearly shown at H, Fig. 3, to increase the amount of heating-surface, and thus facilitate the evaporation of the saccharine liquid contained in the pan. These crimps H are not extended the length of the pan to meet the front and rear walls thereof, but before reaching the same are beveled or tapered off, so as to meet the bottom of the pan at its point of juncture with said front and rear walls, as is clearly indicated in Figs. 1 and 2. This construction is provided to prevent the burning out of the front and rear walls at the points where otherwise the crimps would meet said walls; and, further, to permit the free flow of liquid in the sections, and from one section to another, in the manner to be presently set forth.

The liquid passes from the boiler B by means of the spout b' into the first section of the pan D, and has free flow therein from one side of the crimp H, between the flues E, to the other by reason of the beveling or tapering of the crimp, as described, and thence passes into the second section through the triangular opening or gate h, walled in by the crimp H at that point, the partition d, and the front wall of the pan. At the other end of said partition this triangular opening is closed by an extension or lip, which is made to fit the space to prevent the passage of liquid therethrough. This construction is clearly shown in Fig. 2. The 15 partition dividing the last section from the sirup-compartment extends to the bottom of the pan, the crimp being dispensed with to prevent any burning of the sirup. The saccharine liquid flows through the several sections 20 in the direction of the arrows, and enters as sirup into the first of the sirup-compartments, and thence into the second compartment, the gates e' being provided for that purpose.

Referring to the cast-metal frame C, which 25 serves as a cover for the rear end of the furnace A, and upon which rests the boiler, e marks an opening extending nearly the width of the frame, and adapted to be closed by the damper c', when desired. This opening is provided near the rear wall of the frame, so as to cause the products of combustion to be carried rearwardly beyond the flues E, and be directed against the bottom of the boiler B and its pipes b before entering the return-flues E. It will be noticed that the evaporating-pan is out of contact with the boiler B, and that the intervening space is covered by a top plate, J, of the frame C. The space between this top plate and the bottom 30 of the frame C is divided into a number of sections or spaces by means of partitions j, corresponding in number and in line with the partitions d of the evaporating-pan D. The space j', immediately back of the sirup-compartments, is entirely inclosed to provide a dead-air space 35 to protect the rear wall of the sirup-compartments against the strong heat, and thereby prevent any burning or discoloration of the sirup in said compartments. The other sections have openings L in the bottom of the frame, 40 communicating with the fire-space of the furnace, said openings being ordinarily closed by the individual pivoted dampers K, arranged one in each section. When, after a sufficient quantity of saccharine liquid has been discharged from the boiler into the evaporating-pan, the former may be removed from the frame 45 C, the operator first taking the precaution to close the dampers c'. Upon the removal of the boiler the dampers K, or one or more of them, are opened with the aid of a hook engaging with the eye j² and held in a vertical plane by reason of the projection or rest j³, se-

cured to each of said dampers. When so opened, the dampers close the openings l in the sections of the frame C, when the products of combustion pass from the furnace through the openings L in the bottom of said frame C, and thence into flues E, or one or more sets of them, as desired.

If desired, the damper c' may be made in 70 two parts, to be operated from either side of the frame.

Having thus described my invention, what I claim, and desire to secure by Letters Patent of the United States, is—

1. The evaporating-pan divided into sections by means of partitions d, and provided with crimps H in its bottom, which meet the lower edges of said partitions and are beveled or tapered near the front and rear walls of the 80 pan, and the partitions d, each having an extension or lip at one end, substantially as and for the purpose set forth.

2. The evaporating-pan divided into sections by means of partitions d, each section provided with a set of flues, E, said pan having crimps H in its bottom, arranged between the flues and at the points of partition and beveled or tapered, as described, and the partitions d, each having a depending extension at one end, 90 as set forth, and for the purpose described.

3. The combination, with a furnace having a smoke-box over its front wall, of an evaporating-pan provided with a number of internal flues, the boiler in rear of the pan, and 95 having a number of pipes, b, with closed ends, depending from the bottom thereof, and a metal frame provided with an opening, c, located therein back of the pipes b, as and for the purpose set forth.

4. The combination, with an evaporating-pan provided with a sirup-compartment, of a frame provided with a dead-air space contiguous to said sirup-compartment, substantially as and for the purpose set forth.

5. The combination, with an evaporating-pan provided with a number of internal flues, E, of the metal frame C J, divided into sections, and having the partitions j, the openings L, and the individual pivoted dampers K, as 110 and for the purpose set forth.

6. The furnace having a smoke-box over its front wall, the evaporating-pan provided with a number of internal smoke-flues, and the cast-metal frame C J, having the opening c, the 115 damper c', the partitions j, the openings L l, and the dampers K, in combination, as shown and described.

In testimony whereof I affix my signature in presence of two witnesses.

PHILO S. EWINS.
